US00D983231S

(12) **United States Design Patent** (10) Patent No.: **US D983,231 S**
(45) Date of Patent: **** Apr. 11, 2023**

(54) **CASING CENTRALIZER HAVING SPIRAL BLADES**

(71) Applicant: **Summit Casing Services, LLC**, Fort Worth, TX (US)

(72) Inventors: **Mitchel D. Hansen**, Aledo, TX (US); **Andrew M. Eldridge**, Fort Worth, TX (US)

(73) Assignee: **SUMMIT CASING SERVICES, LLC**, Fort Worth, TX (US)

(**) Term: **15 Years**

(21) Appl. No.: **29/692,649**

(22) Filed: **May 28, 2019**

(56)

(57) **CLAIM**

The ornamental design of casing centralizer having spiral blades, substantially as shown and described.

DESCRIPTION

FIG. 1 is a perspective view of a casing centralizer showing our new design;

FIG. 2 is a rear elevational view thereof;

FIG. 3 is a front elevational view thereof;

FIG. 4 is a right-side elevational view thereof;

FIG. 5 is a left-side elevational view thereof;

FIG. 6 is a top plan view thereof; and,

FIG. 7 is a bottom plan view.

The broken lines showing a cylinder are included for the purposes of illustrating only and form no part of the claimed design.

1 Claim, 6 Drawing Sheets
